CLAIM

The ornamental design for the electric hand tool, as shown and described.

DESCRIPTION

FIG. 1 is a top perspective view of the electric hand tool;

FIG. 2 is a first side view thereof;

FIG. 3 is a second side view thereof;

FIG. 4 is a front view thereof;

FIG. 5 is a bottom view thereof;

FIG. 6 is a top view thereof;

FIG. 7 is a rear view thereof;

FIG. 8 is a top perspective view of a second embodiment of the electric hand tool;

FIG. 9 is a first side view of FIG. 8;

FIG. 10 is a second side view of FIG. 8;

FIG. 11 is a front view of FIG. 8;

FIG. 12 is a bottom view of FIG. 8;

FIG. 13 is a top view of FIG. 8; and,

FIG. 14 is a rear view of FIG. 8.

The broken lines shown in the drawing do not constitute elements of the claimed design.
